DESIGN FOR A TABLE

Chauncey E. Waltman, Chicago, Ill., assignor to
Sandel Manufacturing Co., Chicago, Ill., a cor-
poration of Illinois

Application October 3, 1942, Serial No. 108,411

Term of patent 7 years

To all whom it may concern:

Be it known that I, Chauncey E. Waltman, a citizen of the United States, and resident of Chicago, in the county of Cook and State of Illinois, have invented a new, original, and ornamental Design for a Table, of which the following is a specification, reference being had to the accompanying drawing, forming a part thereof.

The figure is a view in perspective of the table, showing my new design.

The dominant feature of my design comprises a table having a pair of glass panels of substan-

tially rectangular formation arranged in substantially parallel relation to each other and spaced from each other, each of said panels being provided with a border adjacent the periphery thereof which is mirrored and both the longitudinal and transverse sides being curved inwardly intermediate their ends, all as shown.

I claim:

The ornamental design for a table, substantially as shown and described.

CHAUNCEY E. WALTMAN.
